(57) **CLAIM**

The ornamental design for a handle for a utensil, as shown and described.

DESCRIPTION

FIG. 1 is a top plan view of a handle for a utensil according to the present design;

FIG. 2 is a right side elevational view thereof; the left side elevational view being the same;

FIG. 3 is a bottom plan view thereof;

FIG. 4 is a front elevational view thereof; and,

FIG. 5 is a back elevational view thereof.

The broken lines shown FIGS. 1-3 are illustrative of environmental structure only and form no part of the claimed design.
